Des. 217,059
Patented Mar. 31, 1970

217,059

TELEPHONE SET COVER OR SIMILAR ARTICLE

Bruno Todeschini, 25 Via Giovanni Pascoli Cernusco sul
Naviglio, Milan, Italy

Filed Mar. 4, 1969, Ser. No. 16,028

Term of patent 14 years

Int. Cl. D14—03

U.S. Cl. D26—14

FIG. 1 is a top plan of telephone set cover showing my new design;

FIG. 2 is a side elevation of the telephone handset, shown separately for clarity of illustration; and

FIG. 3 is a side elevation of the telephone base.

I claim:

The ornamental design for a telephone set cover or similar article, as shown.
